Application August 20, 1937, Serial No. 71,219
In Great Britain April 26, 1937

Term of patent 14 years

To all whom it may concern:

Be it known that I, Walter William Barling, a subject of the King of Great Britain, residing at 9, 10 and 11, Park Street, Camden Town, London, N. W. 1, England, have invented a new, original, and ornamental Design for a Mouthpiece for Pipes or the like, of which the following is a specification, reference being had to the accompanying drawing, forming part thereof.

In the drawing:

The dominant feature of my invention resides in the unobscured portion of the mouthpiece, which mouthpiece, when viewed from the side, comprises a substantially long thin flat stem the top and bottom surfaces of which stem are parallel throughout substantially two-thirds of its entire length from the tip of the mouthpiece and deviate from the flat and parallel relationship only when approaching the other end of the mouthpiece.

I claim:

The ornamental design for a mouthpiece for pipes or the like substantially as shown and described.

WALTER WILLIAM BARLING.
